UNITED STATES PATENT OFFICE.

EDMUND S. R. BRANDT, OF NEWPORT, RHODE ISLAND.

TORPEDO.

1,388,918.

Specification of Letters Patent. Patented Aug. 30, 192

Application filed April 16, 1921. Serial No. 462,046.

To all whom it may concern:

Be it known that I, EDMUND S. R. BRANDT, a citizen of the United States, residing at Newport, Rhode Island, have invented new and useful Improvements in Torpedoes, of which the following is a specification.

This invention relates to improvements in torpedoes and more particularly to means for cooling the exhaust gases.

10 One of the objects of the present invention is to provide a simple, practical and reliable mechanism or arrangement of parts whereby the exhaust gases from the engine are cooled prior to their leaving the shell of the torpedo thus materially reducing the temperature inside the after-body of the torpedo as well as the visibility of the wake produced by the torpedo.

20 Other objects will be in part obvious and in part hereinafter pointed out in connection with the accompanying sheets of drawing forming part of the present disclosure wherein,

25 Figure 1 is a longitudinal sectional view of the after-body of the torpedo while Figs. 2, 3 and 4 are partial transverse sectional views taken substantially on the lines 2—2, 3—3 and 4—4 of Fig. 1.

30 In Fig. 1 only one of the two exhaust trunks 5 is shown, the other being correspondingly positioned on the opposite side, that is, one on each side of the center line of the torpedo so placed as to avoid fixtures already installed. This trunk 5 is preferably 35 formed of sheet metal pressed to shape and forming with the shell 6 of the torpedo a tube of general triangular cross section, the section diminishing in size from the point of admission of the exhaust gases, that is, 40 at the left of Fig. 1, to the exit thereby caring for the contractions of the gas in cooling.

45 Suitable flanges 8 are provided on the exhaust trunk for riveting, soldering or otherwise securing the same to the shell of the torpedo. Slots are cut in the trunks at points where they pass over the after-body strengthening rings or ribs 10 and holes 11 are made in the latter to assist in the passing of the gases. These rings also serve as 50 baffles thereby to break up the current lines in the flow of gas and give a better radiation of heat and consequent cooling effect.

55 As compared with the present exhaust tubes used in torpedoes the trunks provide the following features:— The cooling of the

exhaust gases, the tapering cross-section area approximating the ideal for contraction of volume due to cooling, increased area at the point where the gases enter the trunk from the turbine chamber of 437%, and increased area at the smallest point of 125% over the present tubes.

The construction, it is believed, will be clear to those skilled in the art and further statement is believed to be unnecessary. The invention is of simple and practical construction, reliable and efficient in operation and is adapted to accomplish, among other all of the objects and advantages herein set forth.

Without further analysis, the foregoing will so fully reveal the gist of this invention that others can by applying current knowledge readily adapt it for various applications without omitting certain features that from the standpoint of the prior art, fairly constitute essential characteristics of the generic or specific aspects of this invention and, therefore, such adaptations should all be intended to be comprehended within the meaning and range of equivalency of the following claims.

What I claim is:—

1. In a torpedo, in combination, exhaust trunks in which the outer shell of the torpedo forms one of the walls thereof.

2. In a torpedo, in combination, exhaust trunks of pressed sheet metal forming with the shell of the torpedo substantially triangular passages of gradually diminishing cross-sectional area.

3. In a torpedo, in combination, exhaust trunks of pressed sheet metal forming with the shell of the torpedo passages of gradually diminishing cross-sectional area, as means in said trunks for breaking up the current lines in the flow of gas.

4. In a torpedo, in combination, exhaust trunks of pressed sheet metal forming with the shell of the torpedo passages of gradually diminishing cross-sectional area, means in said trunks for breaking up the current lines in the flow of gas, said means comprising the strengthening ribs in the shell of the torpedo, said ribs being provided with holes through which part of the gas may pass.

Signed at Newport, Rhode Island, this 6 day of April, 1921.

EDMUND S. R. BRANDT.
